UNITED STATES PATENT OFFICE.

GEORGE W. CAMPBELL, OF HARTFORD, CONNECTICUT, ASSIGNOR TO UNDERWOOD TYPEWRITER COMPANY, OF NEW YORK, N. Y., A CORPORATION OF DELAWARE.

TYPEWRITING MACHINE.

Application filed January 31, 1922. Serial No. 533,027.

To all whom it may concern:

Be it known that I, GEORGE W. CAMPBELL, a citizen of the United States, residing in Hartford, in the county of Hartford and 5 State of Connecticut, have invented certain new and useful Improvements in Typewriting Machines, of which the following is a specification.

The present invention relates to means 10 for locking the carriage of a typewriting machine against movement on the main frame of the machine preliminary to enclosure of the machine in a casing; and for releasing the carriage from such locked condition for the performance of the normal functions of the machine.

An object of the present invention is the provision of means whereby one and the same movable element may serve both to 20 lock the carriage against movement in letter-feed and return directions, and against case-shifting movement.

Another object of the invention is the provision of means whereby the carriage may 25 be released for its normal functions by operation of the usual space-bar.

A further object of the invention is the provision of means whereby the space-bar may be operated independently of the locking device when the latter is in its normal, ineffective position, and when the space-bar is used in typewriting; otherwise expressed, this object of the invention is the provision 30 of means whereby the connections between the space-bar and the locking device are effective only when the carriage is locked.

Other features of the invention are the provision of means for setting the locking device to lock the carriage, independently 40 of the space-bar; the provision of means whereby, when so set, the locking device acts automatically to lock the carriage against movement in letter-feed or return direction when the carriage shall have been moved a 45 sufficient distance in the proper direction; the provision of means whereby the locking device, in locking the carriage against movement in letter-feed or return direction, also locks the carriage in lower-case position; 50 and the provision of means whereby the locking device is normally held against accidental displacement, in ineffective position, and, when set to lock the carriage, is spring-held to the latter until automatic locking takes place.

Other features and advantages will hereinafter appear.

In the accompanying drawings,

Figure 1 is perspective view, from the front, of a portion of the mechanism of an 60 Underwood standard portable typewriting machine, showing the device of the present invention associated therewith.

Figure 2 is a broken view, in side elevation, partly cross-sectional, showing the locking device, and operating connections therefor, in the normal or inoperative position of the same with respect to the platen-carriage. 65

Figure 3 is a view similar to Figure 2, except that the locking device is shown in 70 operative position.

Referring to the drawings, a platen 10 is shown revolvably mounted in the usual manner upon a carriage-frame 11 which is mounted to have letter-feed and return 75 movements on a shift-frame 12. For easy movement of the carriage on the shift-frame 12, the former is provided at the rear with rolls 13 which run on a rail 14 of the shift-frame; and, at the front, a plate 15, which 80 connects the side pieces 16 of the platen-carriage below the platen, rides on rolls or balls 17 supported on a runway 18 on the shift-frame. The mechanism for actuating the shift-frame is not shown. The shift-frame, however, has three case-positions 85 which correspond to the three types 19 shown on the type-bar 20 in Figure 1.

The mechanism for controlling the carriage is urged in letter-feed direction by a 90 spring-drum, not shown, and its letter-feed movement is controlled in the following well-known manner. On the carriage 11 is a rack 21 in mesh with a pinion 22 on a stub-shaft 23 pivotally mounted in a bracket 95 24 in the shift-frame. Fast to the pinion 22 is a ratchet-wheel 25, the rotation of which is controlled by a fixed dog 26 and a loose dog 27, both on a dog-rocker 28. So long, therefore, as the rack 21 is in engagement with the pinion 22, the carriage 100 can have only such movement in letter-feed direction as is permitted by the dog-rocker 28 when the latter is actuated upon operation of a type-key or of the space-bar. The 105 rack 21 is, however, carried by arms (not shown) pivotally mounted on the carriage, so that, if and when desired, the rack 21 may be lifted out of engagement with the pinion 22 to permit the carriage to be moved 110

freely, uncontrolled by the escapement mechanism.

The key-levers, of which one is shown at 29 in Figure 1, are pivoted at their rear on 5 a bar 30. At an intermediate point, each key-lever is provided with a shoulder 31, adapted, when a key 32 is depressed, to engage and depress a universal bar 33 forming part of a bail 34 fast to a rock-shaft 35 10 which is mounted in brackets 36 on the main frame 37. Also fast to the rock-shaft 35 is an arm 38 directed rearwardly and then upwardly, and which at its upper end carries a rearwardly-extending arm or pin 39. The 15 pin 39 projects through a slot 40 in a yoke 41 forming part of the dog-rocker 28. Behind the yoke 41 the pin 39 is provided with a head 42 for engagement with the rear face of the yoke 41. The dog-rocker 28 is 20 pivotally mounted by means of pivot-pins 43 on ears or brackets on the shift-frame. The upper of these ears or brackets 44, only, is shown in Figure 1. The dog-rocker is thus adapted to swing in a horizontal plane 25 around its vertical pivots 43 to move the dogs in and out of engagement with the ratchet-wheel. The slot 40 permits the shift-frame 12, which carries the dog-rocker to be moved between case-positions with respect to the pin or draw-rod 39 on the arm 38, which latter is pivoted to the main frame.

When a type-key is depressed, the universal bar 33 is depressed and the arm 38 35 rocked forward to cause the head 42 on pin 39, by engagement with the rear face of the yoke 41, to swing the dog-rocker 28 around its pivots 43, thus moving the loose dog 27 rearward out of engagement with the ratchet-wheel 25 and bringing the fixed dog 26 into engagement with the tooth of the ratchet-wheel previously engaged by the loose dog. A spring 45 attached to the loose dog and to the rocker thereupon throws the 40 loose dog up to position for engagement with the next tooth of the ratchet-wheel; and, when the type-key is released, a leaf-spring 46, which bears against one of the arms of the bail 34, causes the universal bar 33 and key-lever to return to normal position, and also causes the arm 38 to return to normal position, thus permitting the dog-rocker 28 to be swung on its pivots by a spring, not shown, to move the fixed dog 45 forward out of engagement with the ratchet-wheel, and to bring the loose dog 27 into the path of the succeeding tooth on the ratchet-wheel; whereupon the limited movement of the loose dog on its pivot permits of 50 a letter-feed movement of the carriage under the tension of the spring-drum.

For effecting letter-feed movement of the carriage from the space-bar 47, the latter is secured by arms 48 to a rock-shaft 49 supported in fixed arms 50 on a cross-piece 51

of the main frame; on which rock-shaft is also fixedly secured an arm 52 connected to a link 53, which, in turn, is pivotally connected at 54 to a plate 55 pivoted at 56 on a bracket 57 on the frame piece 37. Fast 70 to, or forming part of, the pivoted plate 55 is an upwardly-projecting arm 58 offset at 59 to project behind the yoke 41 of the dog-rocker 28. The space-bar and its connections just mentioned are held in the normal, Figure 1, position by a spring 60 connected to the rock-arm 52 and fixed arm 50 at the front of the frame. Upon depression of the space-bar against the resistance of the spring 60, however, the link 53 is 75 drawn forward, the plate 55 rocked forward, and the offset 59 behind the yoke 41 of the dog-rocker thereby swung forward to cause the dog-rocker to swing on its pivots 43 in the same manner as when 80 swung through the operation of a type-key. It will be noted that a sufficient clearance is provided between the boss 42^a on the upper end of the arm 38 in which the pin 39 is mounted and the head 42 on the pin 39 to 85 permit the dog-rocker to be swung forward when the space-bar is operated without rocking the arm 38 and the connections thereto from the universal bar and the typ-bars.

Thus far the mechanism described is 90 mechanism which has heretofore been found in the Underwood standard portable type-writing machine; and its description here is given simply for a clear understanding of the manner in which the present invention, now to be described, is associated therewith for the purpose of locking the carriage against accidental displacement when the casing is to be applied.

The locking element of the present invention consists of a finger in the form of an arm 61, pivotally mounted at 62 on a bracket 63 secured by screws 64 to the under face of the cross-piece 37 of the main frame, and carrying at its upper end a dog with a 105 detent flange 65 adapted, in certain positions of the platen-carriage, to register with, and to enter into, a notch or recess 66 in the front edge of the carriage-cross-plate 15. Normally, or in writing position of 110 the parts, the finger 61 is in the Figure 2 position, held forward away from the carriage-plate 15 by means of a leaf-spring 67 secured to the cross-plate 37. It will be noted, see Figure 2, that the finger 61 is 115 extended below its pivot-point 62 to provide a tooth 68 adapted to snap in and out of a V-shaped pocket 69 formed by the leaf-spring 67. When it is desired to lock the carriage, the finger 61, by means of a finger-piece 70 at the upper end thereof, is pushed 120 forward, causing the tooth 68 to snap over the inverted "V" 71 formed in the end of the spring 67; so that, as shown in Figure 3, the spring 67 will cause the finger 61 to be 125 130

pressed against the front edge of the carriage-plate 15. If, while the finger 61 is thus pressed against the carriage-plate 15 by the spring 67, the carriage be moved sufficiently far toward central position from either side, the notch 66 will come into registration with the detent flange 65 on the finger 61; and the finger, under the action of the spring 67, will have a further forward movement to cause the detent 65 to enter the notch 66; thereby locking the carriage against movement to the right or to the left.

As hereinbefore stated, not only is it desirable to lock the carriage against movement to the right or to the left, but it is also desirable to lock the shift-frame 12 down against movement to middle or upper case-positions, when the casing is to be applied. Such locking of the shift-frame may be effected by the detent 65 when overlying the shift-frame 12, as in Figure 3, and also by means of a toe or detent 72 adapted, as shown in Figure 3, to overlie the front edge 25 of the carriage-plate 15 and act directly on the carriage when the arm 61 is thrown rearward against said plate 15. In the Figure 3 position of the parts, therefore, the carriage is not only locked against longitudinal movement on the machine, but is locked down; and, being thus locked down, holds or locks down the shift-frame represented by the rail 14 on which the carriage runs.

35 A feature of the invention has been stated to be a means for unlocking the carriage and the shift-frame by an operation of the space-bar when the machine is to have its normal functions. For effecting such unlocking of the carriage and the shift-frame, the link 53, which, it will be remembered, is drawn forward upon depression of the space-bar, carries a pin 73 which projects laterally across the path of movement of the locking arm 61. 40 When the locking arm 61 is in effective position, see Figure 3, the pin 73 is just behind the same. If, therefore, when the parts are in this position, the link 53 is drawn forward by depression of the space-bar, the pin 45 73 will cause the locking arm 61 to be swung forward out of engagement with the carriage-plate 15. This forward, releasing, movement of the locking arm 61 causes the tooth 68 at the lower end of the latter to snap into the recess 66 in the spring 67, and to be held by the latter in normal, ineffective, position.

It will be noted that the connections between the space-bar and the locking device are such that it is only when the locking device is in carriage-locking position that the space-bar acts upon the same. This one-way acting connection between the space-bar and the locking device permits the space-bar to 60 have its normal functions unencumbered by

connections to the locking device, and precludes actuation of the latter by the space-bar when the carriage is not to be locked.

Variations may be resorted to within the scope of the invention, and portions of the 70 improvements may be used without others.

Having thus described my invention, I claim:

1. In a typewriting machine, a platen, a platen carriage movable in letter-feed and 75 return directions, an escapement mechanism to control the letter-feed movement of the carriage, a space-key and connections therefrom to operate the escapement mechanism, means for locking the carriage against movement in letter-feed and return directions, and means controlled by the space-key for releasing the carriage-locking means. 80

2. In a typewriting machine, a platen, a platen carriage movable in letter-feed and 85 return directions, an escapement mechanism to control the letter-feed movement of the carriage, a space-key and connections therefrom to operate the escapement mechanism, a finger for locking the carriage against 90 movement in letter-feed and return directions and against case-shift movement, means controlled by the space-key for releasing the carriage-locking finger, said carriage-locking finger movable backward and forward of the 95 machine into and out of engagement with a slotted rail of the carriage when the carriage shall have been moved to cause such slot to register with the finger, and a spring for causing the finger to enter the slot when 100 such registration occurs.

3. In a typewriting machine, a platen, a platen carriage movable in letter-feed and return directions, and shiftable between case 105 positions, an escapement mechanism to control the letter-feed movement of the carriage, a space-key and connections therefrom to operate the escapement mechanism, means for locking the carriage against case-shifting movement, and means controlled by the 110 space-key for releasing the locking means.

4. In a typewriting machine, a platen, a platen carriage movable in letter-feed and return directions, and shiftable between case 115 positions, an escapement mechanism to control the letter-feed movement of the carriage, a space-key and connections therefrom to operate the escapement mechanism, means for locking the carriage against case-shifting movement, and connections between the 120 space-key and the locking means for releasing the latter, said connections being disabled when the locking means is in the normal typewriting position.

5. In a typewriting machine, a platen, a platen carriage movable in letter-feed and return directions, and shiftable between case 125 positions, an escapement mechanism to control the letter-feed movement of the carriage, a space-key and connections therefrom to 130

operate the escapement mechanism, means for locking the carriage against movement in letter-feed or return direction, and against case-shifting movement, and means controlled by the space-key for releasing the locking means.

6. In a typewriting machine, a platen, a platen carriage movable in letter-feed and return directions, and shiftable between case positions, an escapement mechanism to control the letter-feed movement of the carriage, a space-key and connections therefrom to operate the escapement mechanism, means for locking the carriage against movement in letter-feed or return direction, and against case-shifting movement, and means controlled by the space-key for releasing the locking means, said locking means comprising a finger having a detent thereon for engagement with a notch in the carriage and adapted in part to overlie the carriage when in effective position.

7. In a typewriting machine, a platen, a platen carriage movable in letter-feed and return directions, a case-shift frame on which said carriage travels, an escapement mechanism to control the letter-feed movement of the carriage, a space-key and connections therefrom to operate the escapement mechanism, means for locking the carriage against movement in letter-feed or return direction, and against case-shifting movement, and means controlled by the space-key for releasing the locking means, said locking means comprising a finger having a detent thereon for engagement with a notch in the carriage and adapted in part to overlie the carriage when in effective position.

8. In a typewriting machine, a platen, a platen carriage movable in letter-feed and return directions, and shiftable between case positions, an escapement mechanism to control the letter-feed movement of the carriage, a space-key and connections therefrom to operate the escapement mechanism, means for locking the carriage against movement in letter-feed or return direction, and against case-shifting movement, means controlled by the space-key for releasing the locking means, said locking means comprising a finger having a detent thereon for engagement with a notch in the carriage and adapted in part to overlie the carriage when in effective position, and means for setting the locking means so that the detent will automatically engage in the notch upon movement of the carriage a sufficient distance in the proper direction.

9. In a typewriting machine, a platen, a platen carriage movable in letter-feed and return directions, a case-shift frame on which said carriage travels, an escapement mechanism to control the letter-feed movement of the carriage, a space-key and con-

nnections therefrom to operate the escapement mechanism, means for locking the carriage against movement in letter-feed or return direction, and against case-shifting movement, and means controlled by the space-key for releasing the locking means, said locking means comprising a finger having a detent thereon for engagement with a notch in the carriage, a toe or stop to overlie the carriage, and a stop to overlie the case-shift frame, when the finger is in effective position, with the carriage in lower-case position.

10. In a typewriting machine, a platen, a platen carriage movable in letter-feed and return directions, and shiftable between case positions, an escapement mechanism to control the letter-feed movement of the carriage, a space-key and connections therefrom to operate the escapement mechanism, means for locking the carriage against movement in letter-feed or return direction, and against case-shifting movement, means controlled by the space-key for releasing the locking means, said locking means comprising a finger having a detent thereon for engagement with a notch in the carriage and adapted in part to overlie the carriage when in effective position.

11. In a typewriting machine, a platen, a platen carriage, an escapement mechanism comprising a dog-rocker to control the letter-feed movement of the carriage, a space-key, a rod or link, having forward and backward movement, connecting the dog-rocker to the space-key, a device movable to and from the carriage to lock and release the latter, and a detent carried by said rod to engage said locking device to release the carriage when the space-key is depressed.

12. In a typewriting machine, a platen, a platen carriage, an escapement mechanism comprising a dog-rocker to control the letter-feed movement of the carriage, a space-key, a rod or link, having forward and backward movement, connecting the dog-rocker to the space-key, a device movable to and from the carriage to lock and release the latter, and a detent carried by said rod to engage said locking device to release the carriage when the space-key is depressed; the locking device being free of said detent in locking operation.

13. In a typewriting machine, a platen, a platen carriage, an escapement mechanism comprising a dog-rocker to control the letter-feed movement of the carriage, a space-key, a rod or link, having forward and backward movement, connecting the dog-rocker to the space-key, an arm pivoted to have movement to and from the carriage, a carriage-locking element on said arm, and a pin or

lug on said rod projecting across the path of movement of said arm to strike and throw the latter to carriage-released position when the space-key is depressed.

5 14. In typewriting machine, a platen, a platen carriage, an escapement mechanism comprising a dog-rocker to control the letter-feed movement of the carriage, a space-key, a rod or link, having forward and backward movement, connecting the dog-rocker to the space-key, an arm pivoted to have movement to and from the carriage, a carriage-locking element on said arm, a pin or lug on said rod projecting across the 10 path of movement of said arm to strike and throw the latter to carriage-released position when the space-key is depressed, and means for effecting a setting of said arm whereby the locking element may act automatically, and independently of said rod, to lock the carriage when the latter has been moved to desired position.

15. In a typewriting machine, a platen, a platen carriage shiftable between case positions, and escapement mechanism comprising a dog-rocker to control the letter-feed movement of the carriage, a space-key, a rod or link, having forward and backward movement, connecting the dog-rocker to the 20 space-key, an arm having a detent thereon for engagement with a notch in the carriage to lock the latter against movement in letter-feed and return directions, and a toe or stop thereon to overlie in part, and lock, the 25 carriage against case-shift movement, and means on said rod for moving said arm to release the carriage.

16. In a typewriting machine, a platen, a platen carriage movable in letter-feed and 30 return directions, and shiftable between case positions, an escapement mechanism to control the letter-feed movement of the carriage, a space-key and connections therefrom to operate the escapement mechanism, 35 means for locking the carriage against case-shifting movement, and means controlled by the space-key for releasing the locking

means, said locking means being disconnected from the space-key in its movement to effective position. 50

17. In a typewriting machine, a platen, a platen carriage movable in letter-feed and return directions, and shiftable between case 55 positions, an escapement mechanism to control the letter-feed movement of the carriage, a space-key and connections therefrom to operate the escapement mechanism, means for locking the carriage against case-shifting movement, and means controlled by the space-key for releasing the locking means, 60 said locking means being also releasable independently of the space-key.

18. In a typewriting machine having a keyboard and a traveling carriage mounted for case-shift movement, a device for locking 65 said carriage against traveling and case-shift movement, and a key in said keyboard for releasing said locking device.

19. In a typewriting machine, the combination with a traveling carriage comprising 70 a bar having a notch therein, of a locking member co-operative with the notch to lock the carriage stationary in a central position for shipment, a spring-detent engaging the locking member to detain it in 75 effective or ineffective position, and a cam on the locking member co-operating with the spring-detent, the cam and detent being so constructed and arranged that the detent urges the locking member toward position to 80 seat in the notch when the locking member is moved against the bar with the carriage away from central position.

20. A locking device for use in typewriting machines, comprising an arm pivoted on 85 the machine-frame and having a detent-flange to interfit with a notch on the carriage-rail, a beak to overlie the carriage-rail and hold it down, and a finger-piece for swinging said lever to effective position.

GEORGE W. CAMPBELL.
